UNITED STATES PATENT OFFICE.

CARL D. CLELAND, OF JEAN, NEVADA.

SPARK-PLUG.

1,346,003.

Specification of Letters Patent. Patented July 6, 1920.

Application filed July 3, 1917, Serial No. 178,429. Renewed December 2, 1919. Serial No. 342,013.

To all whom it may concern:

Be it known that I, CARL D. CLELAND, a citizen of the United States, residing at Jean, in the county of Clark and State of Nevada, have invented new and useful Improvements in Spark-Plugs, of which the following is a specification.

This invention relates to internal combustion engines, and more especially to the 10 sparking igniters therefor, the same being of the make-and-break type having an oscillating electrode; and the object of the invention is to produce a device of this kind which is adapted for use in positions where 15 the actuating mechanism is a rod exerting either a push or a pull intermittently. In other words the device constituting the subject matter of the present invention is an oscillating electrode having a contact arm 20 capable of being set at either side of the spark plug proper, and mechanism at its outer end capable of being set according as the actuating rod exerts a push or a pull.

Details of the preferred construction are 25 set forth in the following specification, and reference is made to the accompanying drawings wherein:—

Figure 1 is a bottom plan view of the 30 plate in which this device is mounted, showing the contact arm in full lines at one side of the spark plug proper, and in dotted lines at the other side of the same.

Fig. 2 is a perspective view of the mechanism carried at the outer side of the plate.

Fig. 3 is a vertical sectional view on about 35 the line 3—3 of Fig. 2, showing the actuating parts as reversed from the position they occupy in Fig. 2.

In the drawings the letter P designates 40 a plate which may be bolted or screwed over an opening in the head of the cylinder, or which in fact might be the head itself, but preferably I make this plate a separate member and circular in contour so that it 45 may be set as desired. Mounted through an insulation bushing I within this plate is a spark plug S to whose outer end leads the feed wire W. No novelty is claimed for this element, excepting that its inner 50 end should have a head 1 consisting of a hard metallic knob or button of such size that it may be ground or turned off as it burns or wears away. This button is electrically connected with the wire W, and the

device as a whole constitutes the fixed electrode.

Fixed through the plate adjacent the insulation is a sleeve 2 within which is mounted a rock shaft 3. Carried by the lower end of this shaft is a collar 4 which in turn carries a rocker arm 5 disposed at right angles to the length of the shaft and adapted to be moved into contact with the button 1. Two stops 6 and 7 depend from the plate P at opposite sides of the fixed electrode, and in Fig. 1 the rocker arm is shown as moving between one stop 6 and the button 1, although it may be adjusted as shown in dotted lines so that it could move between the opposite stop 7 and the button 1 and in that case the movement of course would be in the opposite direction. In either case the circuit is broken when the rocker arm contacts with its stop, whichever stop is in use, and the circuit is closed when the rocker arm is moved so as to contact with the button. Through the outer end of the arm may be fastened a pin or contact point 8 of suitable material to make good electrical contact with the button 1, and this also 80 may be ground or cleaned when it becomes worn or dirty.

Loosely mounted on the upper end of the rock shaft 3 is a hole 13 in the hub 12 of the actuating arm 11 which projects radially 85 from the shaft over the plate P. Mounted on said shaft above the hub 12 is a hole 14 in the hub 15 of the finger 16 which projects outward over the arm 11 and turns downward at its tip alongside said arm, and through said tip and arm are registering holes. Through the latter extends a bolt 17 having expansion springs 18 and 19 coiled on its body under its head and nut and respectively outside the finger and the arm. 90 The hub 15 is held fast on the shaft by a set screw 25, and a screw 24 may take into a socket 23 in the upper end of the shaft if it is thought necessary to connect a ground wire direct with the shaft, although 100 the ground is through the plate and the cylinder in the usual construction of parts. Near the outer end of the arm 11 a hole 21 is formed through it and a groove 22 formed in it, and the rod R (whatever its type and 105 whether it is pushed or pulled) may thereby be connected with the arm.

With the parts constructed as above de-

scribed, it is obvious that when the arm and the finger are removed from the upper end of the rock shaft the latter can be pushed downward so that its rocker arm 5 clears the button 1, and then turned and raised again so as to bring the rocker arm on the other side of the button. In the position shown in full lines in Fig. 1, the rocker arm must move in one direction to 10 close the circuit, whereas in the position shown in dotted lines it must move in the opposite direction, and in either case its outward movement away from said button is checked by its contact with a stop. So 15 also is it possible to replace the actuating arm on the upper end of the rock shaft either side up, and then when the finger is replaced, its depending tip will pass to one side or to the other side of the body of said 20 arm but the holes in these elements will always register. The bolt 17 is now passed through these holes with the spring 18 at one side and the spring 19 at the other side of said members, and the nut applied to the 25 bolt. When now the rod is connected with either the hole 21 or the groove 22 at the outer end of the arm, at each impulse of the eccentric or other mechanism which either pushes or pulls said rod, the arm 11 will 30 be swung away from the finger against the tension of one of the springs, the rock shaft turned, and the rocker arm moved into contact with the button; and when the impulse on the rod R is exhausted, the spring will 35 restore the parts to normal position and break the circuit. Said rod R almost invariably leads transversely across the head of the cylinder, and in a two-cylinder engine there are two such rods which are ordinarily 40 given their impulses by eccentrics on a shaft extending alongside the body of the engine, which shaft is rotated by and in timed relation with the main shaft as well understood. It follows that one rod will exert a push 45 and the other a pull in order to close the circuit and actuate the spark plug, and accordingly the parts of the devices on the two cylinders must be appropriately set. My invention is therefore applicable to 50 either cylinder, and by its adjustability it is applicable to single-cylinder engines or multiple-cylinder engines whose rods R lead in various directions and are variously actu-

ated. I do not wish to be limited to the proportions and materials of parts, nor to 55 details other than as set forth in the following claims.

What is claimed as new is:—

1. In a sparking igniter for internal combustion engines, the combination with a 60 plate, and a fixed electrode therethrough and connected with the source of electricity; of a rock shaft rotatably mounted through the plate adjacent said electrode, a rocker arm projecting radially from said shaft to 65 one side of the fixed electrode, an actuating arm movably mounted on the projecting end of said rock shaft and adapted to be connected at its outer end with the trip mechanism, a finger fixedly and adjustably mounted on said rock shaft beyond the actuating arm and having a downturned tip passing alongside said arm, the downturned tip and the arm being pierced with registering holes, a bolt passing loosely through said holes, 70 and expansive springs coiled on the bolt at opposite sides of the perforated members and under the head and nut of the bolt, for the purpose set forth.

2. In an oscillating-electrode sparking 80 igniter of the type described, the combination with a rock shaft adapted to be mounted through the head of a cylinder and having a threaded socket in its upper end and a rocker arm at its lower end for contact 85 with the fixed electrode, and an actuating arm having at its inner end a hub provided with a hole loosely mounted on the upper end of said shaft and at its outer end means for connection with the trip mechanism; of a finger having at its inner end an upright 90 hole adapted to be mounted on the rock shaft above the hub of said arm and at its outer end a downturned tip adapted to be placed selectively along either side of said arm, the 95 tip and arm being pierced with registering perforations, a bolt extending through said perforations and carrying springs at opposite sides of the finger and tip for holding them normally in contact, a screw in said 100 socket for holding the finger on the rock shaft, and a set screw for permitting its adjustment thereon.

In testimony whereof I affix my signature.

CARL D. CLELAND.
